UNITED STATES PATENT OFFICE.

SAMUEL S. HERSEY, OF AUBURN, MAINE.

FURNACE.

SPECIFICATION forming part of Letters Patent No. 392,804, dated November 13, 1888.

Application filed June 23, 1888. Serial No. 278,008. (No model.)

To all whom it may concern:

Be it known that I, SAMUEL S. HERSEY, of Auburn, in the county of Androscoggin and State of Maine, have invented an Improvement in Furnaces, of which the following description, in connection with the accompanying drawings, is a specification, like letters on the drawings representing like parts.

This invention relates to furnaces of that class in which a steam-generator and hot-air heater are combined in such manner that either may be used separately or both may be used together to produce a maximum heating effect.

My invention has for its object to construct a furnace of the class referred to, as will be described, whereby the same is readily accessible, so that it may be easily cleansed or repaired when required.

My invention therefore consists, essentially, in a furnace, a combustion-chamber or fire-box, a substantially horizontal boiler, and enveloping plates or shells, to form with the said boiler chambers or passages communicating with the fire-box, combined with an enveloping shell forming with the said plates or shells an air-chamber, and with removable caps or covers for the ends of the said shells and boiler, substantially as will be described.

Other features of my invention will be hereinafter pointed out in the claims at the end of this specification.

Figure 1 is a vertical longitudinal section of a furnace embodying my invention; Fig. 2, a rear end view of the furnace shown in Fig. 1; Fig. 3, a rear end view of the furnace shown in Fig. 1 with the outer cap removed; Fig. 4, a rear end view of the furnace shown in Fig. 1 with the outer and inner caps removed; Fig. 5, a front end view of the furnace shown in Fig. 1; Fig. 6, a front end view of the furnace shown in Fig. 1 with the front cap removed, and Fig. 7 a top or plan view of the grate removed.

The base a , herein shown as a hollow frame or casting, preferably of iron, has secured to its opposite ends in any suitable manner, as by rivets, castings a' a'' . The castings a' a'' are provided with openings for the reception of the ends of a substantially horizontal steam-generator, herein shown as the fire-tube boiler a^3 , of any usual or well known construction,

the said boiler being supported at one end, herein shown as the rear end, by lugs a^4 , on a metal plate or shell, a^5 , supported by the said castings, the opposite or front end of the boiler being supported by the casting a' and by flanges a^6 (see Fig. 6) on the said plate, the said boiler being thus inclined from its rear toward its front end to facilitate the passage of the products of combustion through the fire-tubes a^7 .

The metallic plate or shell a^5 is provided near the front end of the boiler, as herein shown, with a preferably circular opening, (see Fig. 1,) about which is extended a depending flange, b , having secured to or forming part of it a cylinder or box, b' , which in practice constitutes the fire-box of the furnace, the grate b^2 of the said fire-box being supported, as shown, in a removable frame or casting, b^3 , (see Fig. 7,) adapted to be fitted into the front end of the base a , the said casting being of suitable depth to form the ash-pit b^4 , having its bottom composed, preferably, of cast-iron, b^5 .

The metallic plate a^5 in practice will preferably extend under and about the lower half of the boiler, and the upper edges or sides of the said plate are bent inward toward the boiler, as at 2, (see Fig. 6,) and are luted or otherwise rendered air-tight therewith, whereby the space or chamber b^6 between the plate a^5 and the lower half of the boiler is maintained separate and distinct from a chamber or space, b^7 , formed by a plate, c , and the upper half of the boiler, the said plate having its ends supported, as shown, by flanges c' c'' on the inner side of the end castings, a' a'' , the edges of the said plate being soldered or luted or otherwise secured to the inturned edges 2 of the plate a^5 . The front end casting, a' , has on its outer side a flange, c^8 , upon which is fitted a cap formed, as shown, by plates c^4 c^5 , the plate c^4 forming with the front head of the boiler a passage, c^6 , through which pass the products of combustion, the plates c^4 c^5 forming a chamber, c^7 , for the passage of air, as will be described. The rear casting, a'' , is provided on its outer side with a flange, d , upon which is fitted a cover, d' , the space between said cover and the rear head of the boiler being divided, as shown, into two chambers, d^2 d^3 , (see Fig. 1,) by the plate d^x .

The chamber d^2 has an outlet-pipe, d^4 , ex-

tended through a flange, d^5 , secured to the casting a^2 , the said flange having fitted upon it a cap or cover, d^6 , which forms around the said flange a chamber, d^7 , which communicates 5 through suitable slots, d^8 , in the casting a^2 with an air chamber or space, d^9 , surrounding the boiler, the said air-chamber being formed by a shell, d^{10} , secured air-tight to the castings a^2 and to the base a , the said shell being provided with one or more outlets, d^{11} , to which are connected the distributing pipe or pipes leading to different parts of the building to be heated, and not herein shown.

In operation the products of combustion 15 pass from the fire-box into the space b^6 below the boiler, as indicated by arrow 20, thence into the chamber d^7 , through the fire-tubes into the chamber c^6 at the front of the boiler, then about the upper half of the boiler, through the 20 passage b^7 into the chamber d^8 , from which they escape through the outlet-pipe d^4 , communicating with the chimney. (Not shown.) The steam generated in the boiler may be taken therefrom through the pipe c , extended through 25 the shell d^{10} , and connected, as shown, to the steam-dome e^1 . Air to be heated is admitted, as herein shown, through a suitable orifice at the rear of the furnace, provided with a door, c^2 , the said air passing upward around the 30 fire-box and boiler in the chambers or spaces d^7 d^9 , the said air heated by contact with the fire-box and boiler being conducted away by suitable pipes (not shown) connected to the outlet-pipes d^{12} . Air may be admitted directly 35 into the chambers c^7 d^7 at the front and rear of the furnace through suitable registers, c^3 c^4 , the air in the chamber c^7 passing therefrom through a pipe, c^9 , into the chamber or passage d^9 .

If it is desired to clean the furnace after considerable use, the front and rear caps, c^3 d^6 , may be readily removed and the air-passages cleaned, and if it is desired to clean the fire-tubes the cap d^7 may also be removed, thus permitting ready access to the said tubes.

To permit the grate b^2 to be readily shaken 45 from outside the furnace, the said grate has a

rod, f , extended toward the front of the furnace and provided with a stud or pin, f^1 , projected up through a slot, f^2 , (see dotted lines, Fig. 7,) in the casting b^2 , (see Figs. 1 and 7,) 50 the said stud or pin having mounted on it a slide, f^3 , and having connected to it, as by a pin, f^4 , (see Fig. 7,) a lever, f^5 , pivoted to a second lever or handle, f^6 , fulcrumed, as herein shown at f^8 , to a lug, f^9 , secured to or forming 55 part of the casting.

I claim--

1. In a furnace, a combustion-chamber or fire-box, a horizontal boiler, plates or shells to form with the said boiler chambers or passages 60 b^6 b^7 , communicating with the fire-box, and an enveloping shell forming with the said plates or shells an air-chamber, combined with removable covers or caps for the ends of the said shells and boiler, whereby the said boiler and 65 shells may be readily inspected and cleansed, substantially as described.

2. In a furnace, a base and end castings, a^2 a^3 , secured thereto, a horizontal fire-tube boiler supported thereby, plates or shells a^5 e , secured 70 to said castings and forming with the said boiler chambers or passages for the products of combustion, a front cap, c^6 , and rear cap or cover, d^7 , combined with an enveloping shell 75 secured to said base and forming an air-chamber, substantially as described.

3. In a furnace, a base and end castings, a^2 a^3 , secured thereto, a horizontal fire-tube boiler supported thereby, plates or shells a^5 e , secured 80 to said castings and forming with the said boiler chambers or passages for the products of combustion, a flange, d^7 , dividing-walls d^8 , and cap or cover d^9 , and front cap, c^6 , combined with an enveloping shell, d^{10} , a flange, d^4 , and cover d^6 , substantially as described.

In testimony whereof I have signed my name to this specification in the presence of two subscribing witnesses.

SAMUEL S. HERSEY.
